UNITED STATES PATENT OFFICE.

CHAUNCEY B. CRAGIN, OF ADA, MINNESOTA.

NUT-LOCK.

SPECIFICATION forming part of Letters Patent No. 297,678, dated April 29, 1884.

Application filed January 19, 1884. (No model.)

To all whom it may concern:

Be it known that I, CHAUNCEY B. CRAGIN, a citizen of the United States, residing at Ada, in the county of Norman and State of Minnesota, have invented certain new and useful Improvements in Nut-Locks, of which the following is a specification, reference being had therein to the accompanying drawings.

10 My invention relates to an improvement in nut-locks, the object being to provide a locking device which will be rendered more secure by any movement of the nut in unscrewing.

15 The invention consists in a bolt having a transverse slot near its threaded end and outside of the nut, and a peculiar key having projections at its ends adapted to fit within such slot; also, in combining with the bolt, 20 nut, and key so constructed a spring interposed between the nut and the fish-plate, so that it will yield sufficiently to allow a slight forward movement of the nut when the key is to be removed; and these features will be more 25 fully hereinafter described.

In the drawings, Figure 1 is a longitudinal section of a bolt, showing a rail and fish-plate in cross-section. Fig. 2 is a separate view of the key. Fig. 3 shows a modified form of 30 nut and key. Fig. 4 is another modification of the key. Fig. 5 is a plan view of the spring.

A represents a rail, and B a fish-plate, of ordinary construction.

35 C is a bolt threaded at one end, and having near such end a transverse slot, a.

D is the nut screwed up against the fish-plate, the slot a being wholly exterior to such nut.

40 E represents the locking-key, of which a separate view is shown in Fig. 2. This key is a small piece of iron or steel of approximately the same length as the diameter of the nut. At each end of the key is a projection at right angles to the direction of its 45 length. The projection b is of such length that it will just pass through the slot a, while the projection c is considerably longer, and extends some distance beyond the edge of the 50 slot. The sides of the key and slot are parallel.

It is clear that when the parts are in position the tendency of the nut to unscrew will cause it to bear firmly against the key, forcing the latter outward, so that both projec-

tions b and c overlap the edge of the slot, making it impossible to withdraw the key. This pressure is increased by the insertion of a stiff spring, d, between the nut and fish-plate, which tends to throw the nut outward, 60 and bears firmly on the fish-plate. The spring may be made of a ring of steel split at one point, and having one or both ends slightly turned from the plane of the circle. It is, however, not absolutely essential that this spring 65 be employed, though I prefer to use it.

I have shown in Fig. 3 a modified form of nut and key. Here the projections b extend in opposite directions, and the nut is provided with a circular flange, f, on its face, into which 70 one of the projections sets, the other overlapping the outer edge of the slot.

In Fig. 4 the key is shown as of a double T shape, the heads being just long enough to pass through the slot. A quarter-turn is given the 75 key, so that the heads extend transversely across the slot, and the nut bears upon one of the flat sides of the key. In all these modifications the spring may be used, if thought preferable.

80 The operation of the device needs no lengthened description. The nut is screwed on and the key inserted in the slot. Any loosening of the nut results in tightening the key, and such key can only be removed by screwing the nut inward against the yielding pressure of the spring the slight distance necessary to permit of its withdrawal. In locking the nut after the key is inserted, the nut is turned back on the bolt, so that it bears firmly in the 85 first instance upon the face of the key.

Having described my invention, I claim—

1. The combination, with a slotted bolt and its nut, of a transverse key having a projection at right angles at each end, substantially 90 as and for the purposes set forth.

2. The combination, with the slotted bolt and the fish-plate, or other structure through which such bolt passes, of the key having outwardly-extending projections arranged to 95 overlap the edges of the slot, and the spring interposed between the fish-plate and the nut, substantially as described.

In testimony whereof I affix my signature in presence of two witnesses.

CHAUNCEY B. CRAGIN.
